DESIGN FOR A DISPENSER FOR INTER-FOLDED SHEETS

Byron T. Hoffmaster, Menasha, Wis., assignor to Marathon Paper Mills Company, Rothschild, Wis., a corporation of Wisconsin

Application September 17, 1943, Serial No. 111,147

Term of patent 14 years

To all whom it may concern:

Be it known that Byron T. Hoffmaster, a citizen of the United States, residing at Menasha, Winnebago County, in the State of Wisconsin, has invented a new, original, and ornamental Design for a Dispenser for Interfolded Sheets, of which the following is a specification, reference being had to the accompanying drawings, forming a part thereof.

Figure 1 is a perspective view of the dispenser for interfolded sheets, showing my new design;

Figure 2 is a side elevational view thereof; Figure 3 is a front elevational view; Figure 4 is a perspective view of the dispenser as seen from the rear and bottom thereof; and Figure 5 is a view of the dispenser in section on lines 5—5 of Figure 1, and in the direction of the arrows.

I claim:

The ornamental design for a dispenser for interfolded sheets, as shown.

BYRON T. HOFFMASTER.
